PAGE 2

Fig. 3

Fig. 1

Fig. 2

FIG. 1 is a perspective view of toy molding press, showing our new design.

FIGURE 2 is a side elevational view thereof.

FIGURE 3 is a top plan view thereof.

FIGURE 4 is a front elevational view thereof.

FIGURE 5 is a rear elevational view thereof.

FIGURE 6 is a bottom plan view thereof.

The broken line showing of a removable die in FIGS. 2, 4 and 5 is for illustrative purposes only.

We claim:

The ornamental design for a toy molding press, substantially as shown and described.
